UNITED STATES PATENT OFFICE.

DAVID J. CONANT, OF PITTSBURGH, PENNSYLVANIA, ASSIGNOR TO WESTINGHOUSE ELECTRIC & MANUFACTURING COMPANY, A CORPORATION OF PENNSYLVANIA.

COLLECTOR RING.

Application filed March 31, 1927. Serial No. 179,762.

My invention relates to current-collecting devices and it has particular relation to composite slip rings.

The object of my invention is to make a slip ring having an active surface material of known uniformity, requiring fewer machine operations and consisting of cheaper material than slip rings heretofore known in the art.

10 Cast brass or bronze slip rings usually contain air holes or sand inclusions which, if present on the finished surfaces, render the rings unsuitable.

Cast-copper slip rings have been utilized 15 but they cannot be utilized alone because the copper stretches in use, probably due to repeated heatings and contractions, so that, eventually, they become loosened from the supporting cylinder on which they are 20 mounted.

It has been customary, in the past, to provide cast-copper slip rings of U or T-shape in cross section, having a steel ring shrunk upon the base member of the copper ring 25 for the purpose of holding it in clamped engagement against the supporting cylinder and positively preventing the loosening thereof, as set forth in the patent to Siegfried & Jungk, No. 1,281,862, granted October 15, 1918, and assigned to Westinghouse Electric & Manufacturing Company.

Rolled sheet copper, on the other hand, is a homogeneous material, a good conductor and eminently suited for collector rings except for its property of continually stretching, as pointed out in the patent to Mills No. 1,393,564, granted October 11, 1921, and assigned to Westinghouse Electric & Manufacturing Company. It has heretofore been 40 impossible, however, to utilize sheet copper for collector rings because of the difficulties encountered in securing it in place so that it will not work loose in operation.

According to my invention, I utilize a 45 steel inner ring, with sheet copper rolled, spun or pressed over it. My invention is illustrated in the accompanying drawing, wherein

Figure 1 is a longitudinal sectional view 50 of a current-collecting device of my invention,

Fig. 2 is an end elevation of the same in position on the motor shaft, and

Figs. 3 and 4 are sectional views illustrating the process of manufacture.

As shown in the drawing, my invention comprises a cylindrical member 2 carried by a shaft 3, and one or more slip rings 4 tightly embracing an insulating covering 5 on the cylindrical member, being preferably secured thereto by means of a press fit. Each slip ring comprises an inner ring 7 of steel or, in general, of a material of relatively poor conductivity, but capable of retaining its tight fit on said cylinder member for an indefinitely long period of time, and a single sheet 8 of a good conductor, such as copper, wrapped around said inner ring, as by means of rolling, spinning or pressing operations, whereby a portion 9 of the copper sheet extends inside of the iron ring 7, between the iron ring and the supporting cylindrical member 2 on which the slip ring is mounted. It will be further observed that another portion 10 of the copper sheet extends outside of the iron ring, and provides an ideal current-collecting surface for the device.

A convenient method of making the slip ring just described is to place a copper blank 8^a between the steel ring 7 and a die 11 having an annular groove 12, as shown in Fig. 3. Sufficient pressure is then applied, through a plate 13, to force the steel ring 7 into the groove 12 of the die, and also to upset the outer portion 10 of the copper ring 8^a to a greater thickness than the original blank 8^a or the inner portion 9. The copper is thus practically extruded into the die. A thickened surface portion 10 is preferred, in order that a larger quantity of active 85 wearing material may be provided, and also to provide for the trimming of the slip-ring surface. As the slip rings 4 are all made from a die of uniform size, the bores of the finished rings do not require turning before 90 assembly on the supporting cylinder 2.

I claim as my invention:

1. A collector ring for electrical apparatus comprising a steel ring and a continuous sheet of copper bent thereover and extending adjacent to both the inner and outer surfaces of said ring.

2. A current-collecting device comprising a shaft, a cylindrical member carried thereby and a slip ring tightly embracing said cylindrical member, said slip ring comprising an inner ring of a material of relatively poor conductivity but capable of retaining its tight fit on said cylindrical member for an indefinitely long period of time and a 110

- single sheet of a good conductor wrapped around a plurality of sides of said inner ring, including the inside, between said inner ring and said cylindrical member.
5. 3. A collector ring comprising an inner ring of a material having an enduring elastic limit in tension higher than copper and an extruded copper member tightly embrac- ing both the inner and outer surfaces of said ring.
4. An extruded copper slip ring having an embedded iron core.

In testimony whereof, I have hereunto subscribed my name this 25th day of March, 1927.

DAVID J. CONANT.
